UNITED STATES PATENT OFFICE

132,431

DESIGN FOR A MOLDED FIBER COMBINATION PLATE

Charles J. Chaplin, South Portland, Maine, assignor to Chaplin Corporation, South Portland, Maine, a corporation of Maine

Application September 23, 1940, Serial No. 95,386

Term of patent 14 years

To all whom it may concern:

Be it known that I, Charles J. Chaplin, a citizen of the United States, residing at South Portland, county of Cumberland, State of Maine, have invented a new, original, and ornamental Design for a Molded Fiber Combination Plate, of which the following is a specification, reference being made to the accompanying drawing, forming a part thereof.

Fig. 1 is a top perspective view of a molded fiber combination plate, showing my design;

Fig. 2 is a bottom perspective view thereof;

Fig. 3 is a bottom plan view; and

Fig. 4 is a fragmentary sectional view on the line 4—4 of Fig. 3 and in the direction of the arrows.

The above application is a continuation in part of Serial No. D-93,881 filed July 20, 1940.

What I claim is:

The ornamental design for a molded fiber combination plate, as shown.

CHARLES J. CHAPLIN.
